US0D1001213S

(12) **United States Design Patent** (10) **Patent No.:** **US D1,001,213 S**
(45) **Date of Patent:** **** Oct. 10, 2023**

(54) **ROWING MACHINE**

(71) Applicant: **Liking Limited**, Hong Kong (CN)

(72) Inventor: **Zifeng Fu**, Hong Kong (CN)

(73) Assignee: **Liking Limited**, Hong Kong (CN)

(**) Term: **15 Years**

(21) Appl. No.: **29/871,095**

(22) Filed: **Feb. 11, 2023**

(51) LOC (14) Cl. **21-02**

(52) U.S. Cl.

USPC **D21/674**

(58) **Field of Classification Search**

(57) **CLAIM**

The ornamental design for a rowing machine, as shown and described.

DESCRIPTION

FIG. 1 is a front top perspective view in accordance with a rowing machine;

FIG. 2 is a top view of the design of FIG. 1;

FIG. 3 is a bottom view of the design of FIG. 1;

FIG. 4 is a right-side view of the design of FIG. 1;

FIG. 5 is a left-side view of the design of FIG. 1;

FIG. 6 is a front view of the design of FIG. 1;

FIG. 7 is a rear view of the design of FIG. 1; and,

FIG. 8 is a rear top perspective view of the design of FIG. 1.

The broken lines form no part of the claimed design.

1 Claim, 7 Drawing Sheets
